US0D1017978S

(12) United States Design Patent (10) Patent No.: US D1,017,978 S
(45) Date of Patent: * Mar. 19, 2024

(54) SLIPPER

(71) Applicant: Fujian Jingyuan Network Technology Co., Ltd., Quanzhou (CN)

(72) Inventor: Wenliang Lin, Fuqing (CN)

(73) Assignee: Fujian Jingyuan Network Technology Co., LTD., Quanzhou (CN)

() Term: 15 Years

(21) Appl. No.: 29/900,715

(22) Filed: Aug. 24, 2023

(30) Foreign Application Priority Data

Aug. 2, 2023 (CN) 202330489867.8

(51) LOC (14) Cl. 02-04

(52) U.S. Cl.

USPC D2/919; D2/897

(58) Field of Classification Search

USPC D2/896, 897, 900, 902, 904, 906–908, D2/916–924, 925–945, 947–960, 969–979
